UNITED STATES PATENT OFFICE.

JOHN W. BELL, OF SHENANDOAH, PENNSYLVANIA.

REVERSING-VALVE.

No. 920,524.

Specification of Letters Patent.

Patented May 4, 1909.

Application filed August 10, 1907. Serial No. 388,009.

To all whom it may concern:

Be it known that I, JOHN W. BELL, a citizen of the United States, and a resident of Shenandoah, in the county of Schuylkill and 5 State of Pennsylvania, have invented a new and useful Improvement in Reversing-Valves, of which the following is a full, clear, and exact description.

The purpose of the invention is to provide 10 a reversing valve adapted to any engine or steam pump, which valve is exceedingly simple and positive in its action, and is so constructed that when the reversing valve is closed it completely shuts off all communication 15 between the pressure chamber, back of the reversing valve, and the cylinder, with the exhaust ports leading from the chambers at the ends of the slide valve, thus preventing a loss of power from the cylinder through 20 a reverse valve chamber, which latter feature stops all interference with the operation of the slide valve and auxiliary plunger therefor when used, by reason of counter-pressure 25 leaking from the back of the reverse valve.

25 A further purpose of the invention is to provide a construction of reversing valve that will effectually act to close the ports to which it is adapted, no matter what the wear of the parts may be.

30 The invention consists in the novel construction and combination of the several parts as will be hereinafter fully set forth and pointed out in the claims.

Reference is to be had to the accompanying 35 drawings forming a part of this specification in which similar characters of reference indicate corresponding parts in both the figures.

Figure 1 is a vertical section through the 40 steam cylinder and chest of a steam pump, and a section through the applied reversing valve; and Fig. 2 is an enlarged vertical section through the valve and casing.

Although I have shown the reversing valve 45 applied to a steam pump of the Cameron type, I desire it to be understood that said valve may be applied with equally good results to any type of steam engine.

A represents a piston driven by steam admitted under a slide valve B in the steam chest B', which as it is shifted backward and forward alternately connects with opposite ends of the cylinder C through the medium of the ports 10 and 11 that act alternately as 50 supply and exhaust ports for the cylinder. The slide valve in the construction set forth

is shifted by a plunger B². This plunger is hollow and is filled with steam that passes out through a hole at each end and fills the spaces 12 and 13 between it and the heads of 60 the steam chest in which it works. Pressure being equal at each end of the plunger B² it is, under ordinary conditions, balanced and motionless, but when the steam piston A has traveled far enough to strike and open a reversing valve D, to be hereinafter particularly described, the steam exhaust passes through a port E, one of which leads from each of said spaces 12 and 13, causing the plunger to immediately shift and carry with 65 it the valve B, thus reversing the stroke of the piston A. No matter in what direction the piston is traveling, it must instantly reverse on touching the valves D. The plunger B² in its movement acts as a slide valve 70 to close the ports E, and is cushioned on the confined steam between the ports and steam chest cover.

The reversing valves D are closed as soon as the piston A leaves them, by a constant 80 pressure of steam entering behind them through ports 14 that lead from the steam chest through the casings D' for the valves. The casings D' may be integral portions of the cylinder C or may be attached thereto in 85 any suitable manner. Each casing D' is provided with a chamber D² and this chamber D² is provided with a cylindrical outer section 15 and an intermediate conical section 16, which latter section at its reduced 90 end portion connects with a cylindrical section 16^a, that is much smaller in diameter than the rear cylindrical section 15. Where a casing D' engages the cylinder C, it is sometimes desirable to have stepped keys 17 95 formed therein as extensions from the central portion of the inner face of the casing, as is shown in the drawings, but the said stepped keys 17 may be omitted. When used they constitute bearings for the inner 100 ends of the valves D operating in said casings.

Each valve D corresponds in exterior contour to the interior contour of the casing or valve chamber D²; that is to say, each valve 105 D consists of a rear cylindrical section 18 of sufficient size and length to move freely in the cylindrical section 15 of the valve chamber D², and a conical intermediate section 19, at the reduced end of which a cylindrical 110 stem section 20 is formed integral with the body portion of the valve, and in the closed

position of the valve the stem 20 thereof extends into the cylinder C.

Each valve casing D' is provided with an open exhaust port E', that constitutes a continuation of the exhaust port E carried from the steam chest and hereinbefore described. The exhaust ports E' connect with the chamber D² of the valve casing or bushing at its conical section 16, and immediately opposite the entrance of the port E' a second exhaust port E² is carried from the bottom portion of the conical section 16 of the valve chamber and thence to the exhaust port for the steam chest, as is shown by dotted lines in the drawings.

It will be observed that the conical section of a valve when the valve is in closed position crosses the ports E' and E², and having a tapering connection with the walls of the chamber D² effectually closes said ports, and also the valve so fits in the chamber D² as to prevent any fluid passing out except when the valve is pushed outward to its open position for the passage of exhaust steam through the ports E, E', and E². Such a valve will wear perfectly for a long period of time, but in order to compensate for possible wear, rings 21 are fitted in grooves produced in the periphery of the inner cylindrical section 18 of the valve, as is also shown in the drawings, and these rings 21 correspond to the ordinary steam packing rings. Each casing or bushing D' is provided at its outer end with a detachable cap D³ which admits of the ready withdrawal of a valve from a casing, or the introduction of a valve therein.

In the construction described, when the reversing valve is closed it completely shuts off all communication between the pressure chamber back of the reversing valve and the cylinder, with the ports E, E', and E², thus preventing a loss of power from the cylinder through the release valve exhaust and the escape of pressure into the port E from the pressure chamber back of the reversing valve. This latter feature stops all interference with the operation of the plunger B² by the accumulation of counter-pressure leaking from the back of the release valve.

Having thus described my invention, I claim as new and desire to secure by Letters Patent,—

1. A combination with a cylinder, a piston in the cylinder, a steam chest, a slide valve in the steam chest, and a plunger for

operating the valve, of casings at the ends of the cylinder, each casing being provided with a chamber having an outer cylindrical section, an inner cylindrical section smaller than the outer section, and an intermediate conical section, said chamber being provided with ports leading from the upper portions of their conical sections to the ends of the steam chest, ports leading from the lower portions of said conical portions to the exhaust port of the steam chest, and ports establishing communication between the outer sections of the chambers and the steam chest intermediate of the ends thereof, and valves having cylindrical outer sections, inner cylindrical sections smaller than the outer sections and intermediate conical sections, said valves being mounted in the said chambers and having their smaller inner ends projecting into the cylinder.

2. In reversing valves, the combination with a casing having a chamber constructed with a rear cylindrical section, a forward or inner cylindrical section of lesser diameter than the rear section, and an intervening conical section, the said casing being also provided with an exhaust port leading from its upper portion to the upper part of the conical section of the chamber, being in communication therewith, and a second exhaust port communicating with and leading from the lower part of the conical section of the said valve chamber, of a valve mounted to slide in the said chamber, which valve comprises a rear cylindrical section provided with an inserted peripheral ring, or rings, an inner cylindrical section of lesser diameter, and an intermediate or intervening conical section, the latter section being adapted to cross the ports where they enter the valve chamber, the said valve in its external contour corresponding to the contour of the said valve chamber, and the said valve in its inner or smaller cylindrical section being of sufficient strength to extend out beyond the casing into the main cylinder when the valve is in a closed position.

In testimony whereof I have signed my name to this specification in the presence of two subscribing witnesses.

JOHN W. BELL.
